FIG. 1

FIG. 2

INVENTOR:

Stanley Frederick Hans.

UNITED STATES PATENT OFFICE

2,678,857

SURGICAL OPERATION TABLE ILIAC-CREST SUPPORT

Stanley Frederick Hans, London, England

Application November 17, 1952, Serial No. 320,997

10 Claims. (Cl. 311—10)

1 This invention relates to surgical operation table iliac-crest supports. As is well known, it is often necessary for surgical operation tables to be inclined with the patient's head at the lower end of the table (as for example in the Trendelenburg position). In order to prevent the patient from slipping down the table there may be used shoulder rests (which have the disadvantage that they sometimes lead to brachial palsy), or the patient's legs may be bent over the upper end of the table (which is disadvantageous in that it is difficult to adjust the table correctly and calf and popliteal thrombosis may be caused). It has therefore been proposed to use iliac-crest supports, but these have not found general acceptance because operation theatre technicians require experience to be able to adjust them properly, the supports sometimes twist into incorrect positions, the padding tends to twist off them after a little use, different sizes are required to fit correctly against iliac crests of different sizes, and they are of fixed height and may obstruct the surgeon.

One object of the present invention, therefore, is to provide an improved iliac-crest (pelvic) support for use in connection with a surgical operation table.

According to the invention a surgical operation table iliac-crest support comprises a rotatable roller-like element which is symmetrical about its axis of rotation and has a concave profile adapted to fit comfortably against a patient's iliac crest. Preferably the roller-like element is mounted for free rotation upon a spindle which is laterally adjustable in position. In a particularly advantageous construction the roller-like element is freely movable axially so that it can assume or be placed at the height best suited to the patient. The roller-like element may be padded to prevent bruising the patient.

It will of course be understood that the supports are used in pairs; the roller-like elements are applied to the waist of the patient with the table horizontal, and as the table is tilted slipping of the patient brings the iliac crests into engagement with the profiled surfaces of the said elements, and the supports are thus largely self-adjusting and their application is very easily effected without particular skill or experience. The profile of the roller-like elements may be substantially anatomically correct, and the supports will then fit any normal iliac crest sufficiently accurately. Being symmetrical and rotatable, the roller-like elements always present a suitable bearing surface for the iliac crest; and

2 being axially movable, the elements assume the appropriate height without impeding the surgeon.

In the accompanying drawing an iliac-crest (pelvic) support according to the invention is illustrated by way of example,

Figure 1 being a sectional side elevation of the support, and

Figure 2 a perspective view of the support.

Referring to the said drawing, the support comprises a spigot which has a portion 10 of square cross-section, a cylindrical portion 11, and a screw-threaded portion 12. An arm 13 has a slot 14 through which the screw-threaded portion 12 of the spigot passes freely, and on the portion 15 12 are a washer 15 and a hand-nut 16, and thus by rotation of the nut 16 the arm 13 can be clamped tightly between the washer 15 and the portion 11, or released, as desired. A spindle 17 is screwed through a metal pad 18 and the arm 13; the pad 18 may be brazed or welded to the arm 13, and the spindle 17 may also be additionally secured by brazing or welding. On the spindle 17 is a freely-rotatable axially-movable roller-like element comprising a lower part 19, an upper part 20, a sponge rubber sleeve 23 for padding and a sleeve 24 of soft solid rubber. The parts 19 and 20 are formed separately so that they can be easily inserted from opposite ends into the sleeve 23, which fits tightly and is preferably bonded to the parts 19 and 20 after the latter have been screwed together. The sleeve 24 is bonded to the sleeve 23, of which the end surfaces are sealed in conventional manner. A spring clip 21 is secured in an annular groove in the spindle 17, and upward movement of the roller-like element is limited by an internal shoulder in the part 20 engaging this clip 21. A cap 22 is provided to close the upper end of the bore of the roller-like element. As can be seen, the roller-like element is symmetrical about its axis of rotation and has a concave profile adapted to fit comfortably against a patient's iliac crest.

The supports are used in pairs, in the following manner. With the patient on the horizontal operation table, the square portions 10 are dropped into existing square sockets on the table as indicated in Figure 1, the arm 13 extending over the top of the operation table (not shown) and the spindle 17 being substantially perpendicular to the top of the operation table; the nuts 16 are loosened, the roller-like elements are applied to the waist of the patient, and then the nuts 16 are tightened. As the table is tilted, the iliac crests come into appropriate contact with the roller-like elements.

Obviously modifications can be introduced into the construction without departing from the invention as claimed below.

I claim:

1. A surgical operation table iliac-crest support, comprising a roller-like element rotatable about its longitudinal axis, said element being symmetrical about its longitudinal axis and having a concave profile to fit an iliac crest, and attachment means for mounting said element on an operation table.

2. A support as defined in claim 1, said attachment means being adjustable.

3. A support as defined in claim 1, said element being axially movable.

4. A support as defined in claim 1, said attachment means being adjustable and said element being axially movable.

5. A surgical operation table iliac-crest support comprising an arm, attachment means for mounting said arm on an operation table, a spindle secured to said arm, and a roller-like element rotatably mounted on said spindle, said element being symmetrical about its axis of rotation and having a concave profile to fit an iliac crest.

6. A support as defined in claim 5, said attachment means permitting adjustment of the location of said arm.

7. A support as defined in claim 5, said element being axially-movable on said spindle.

8. A support as defined in claim 5, said attachment means permitting adjustment of the location of said arm and said element being axially-movable on said spindle.

9. A surgical operation table iliac-crest support comprising an arm, means for clamping said arm in varying location on an operation table, a spindle secured to said arm, a roller-like element freely rotatable and axially movable on said spindle, said element being symmetrical about its axis of rotation and having a concave profile to fit an iliac crest, and means limiting the axial movement of said element.

10. A support as defined in claim 9, said roller-like element comprising a lower part and an upper part connected together, and a sleeve of resilient material fitting tightly to said lower part and upper part.
